CLAIM

The ornamental design for a pet toy as shown and described.

DESCRIPTION

FIG. 1 is a top perspective view of a pet toy in accordance with my new design;

FIG. 2 is a bottom perspective view thereof;

FIG. 3 is a top rear view thereof;

FIG. 4 is a bottom view thereof;

FIG. 5 is a right side view thereof;

FIG. 6 is a left side view thereof;

FIG. 7 is a front view thereof; and,

FIG. 8 is a back view thereof.

The broken lines in the drawings illustrate portions of the pet toy that form no part of the claimed design.
